UNITED STATES PATENT OFFICE.

ALBERT ERICKSON, OF CHICAGO, ILLINOIS, ASSIGNOR TO SPLITDORF ELECTRICAL COMPANY, OF NEWARK, NEW JERSEY, A CORPORATION OF NEW JERSEY.

IGNITION DEVICE FOR INTERNAL-COMBUSTION ENGINES.

Application filed July 21, 1919. Serial No. 312,229.

To all whom it may concern:

Be it known that I, ALBERT ERICKSON, a citizen of the United States, residing at Chicago, in the county of Cook, State of Illinois, have invented certain new and useful Improvements in Ignition Devices for Internal-Combustion Engines, of which the following is a description, reference being had to the accompanying drawing and to the figures of reference marked thereon.

The invention relates to new and useful improvements in ignition devices, and more particularly to an ignition device having a fixed and a movable electrode to which current is supplied by a magneto generator.

An object of the invention is to provide an ignition device of the above character, wherein the fixed and movable electrodes are supported by a member or part which is readily detachable from the bracket carrying the magneto generator, whereby new electrodes may be readily substituted for the old ones without requiring any changes in the bracket structure which carries the magneto generator.

A further object of the invention is to provide a device of the above character, wherein the spring for holding the electrodes closed is supported by the part or member carrying the electrodes.

A still further object of the invention is to provide a device of the above character, wherein the fixed electrode has a sliding detachable connection with a terminal member on the bracket carrying the magneto generator, so that the electrodes may be separated from the magneto generator without disconnecting any parts.

These and other objects will in part be obvious and will in part be hereinafter more fully disclosed.

In the drawings which show by way of illustration one embodiment of the invention—

Figure 1 is a perspective view showing a portion of an engine cylinder, the pad carried thereby, the supporting stud for the bracket carrying the magneto and the electrodes, together with the supporting means therefor;

Figure 2 is an end view of the magneto generator showing the supporting bracket therefor;

Figure 3 is a vertical sectional view through a portion of the engine cylinder and

a portion of the bracket carrying the magneto generator;

Figure 4 is a horizontal sectional view of the same.

The invention is directed broadly to an ignition device having a fixed and a movable electrode with which is associated a magneto generator for supplying current for ignition. The magneto generator is carried by a bracket which is detachably mounted on the engine cylinder. Said bracket is formed with an opening which is adapted to register with the opening in the engine, which is adapted to receive the spark plug which includes the fixed and movable electrodes and the supporting member or part therefor. This spark plug extends outwardly away from the cylinder to the engine and into an opening in the bracket, said opening being shaped to conform generally to the shape of the projecting plug and fitting snugly around the same. Said projecting plug is formed with a shoulder which overlaps the edge of the opening in the bracket, so that when the bracket is bolted on the engine cylinder, it serves also to hold the spark plug or support for the electrodes in place in the engine cylinder. The spring for normally holding the electrodes closed is wound about the shaft carrying the movable electrode and is, therefore, supported by the member which carries the electrodes. The fixed electrode has a projecting rod which has a sliding engagement with an insulated terminal on the magneto bracket, which is in turn connected with the magneto generator.

Referring more in detail to the drawings, I have shown my invention as applied to an ignition device which includes a magneto generator G, a fixed electrode 1, carrying a contact point 2, a movable electrode 3, carrying a contact point 4, which is adapted to engage the contact point 2. The fixed electrode 1 is carried by a rod 5, which is mounted in an insulating sleeve, and said insulating sleeve is in turn mounted in a spark plug or supporting member 6. The movable electrode 3 is carried by a shaft 7 which is likewise mounted in this spark plug or supporting member 6. The supporting member 6 is tapered, so as to fit snugly the tapered opening in the wall of the cylinder, which cylinder is indicated at C in the drawings. On the outer end of the shaft 7, there is an arm

8, which is fixed to the shaft. A spring 9 encircles the shaft between the arm and the supporting member 6 and is connected at one end to said arm and at its other end to 5 the supporting member 6. This spring holds the movable electrode shaft seated and the contact points 4 and 2 in engagement with each other. The magneto generator G is carried by a bracket 10. Said bracket is 10 formed with a shelf 11, to which the magneto generator is bolted by suitable bolts 12. The magneto generator is provided with a trip lever 13, and this trip lever is operated by means of a main spring 14. The particular construction of the magneto and the actuating means therefor forms no part of the present invention, but is shown, described and claimed in my co-pending application 15 Serial No. 312,228, filed of even date here- 20 with.

The bracket 10 is formed with a face member 15 which is provided with an opening 16 adapted to surround the projecting end of the spark plug or supporting member 6. Said spark plug or supporting member 6 is provided with a shoulder 17, which is adapted to overlie the edge of the opening 16. The bracket 10 has an opening 18 which extends over a stud 19 carried by the 25 pad 20 formed on the engine cylinder, and a nut 21 on the end of said stud clamps the bracket firmly against the pad 20 and at the same time causes the bracket to firmly clamp the spark plug or supporting member 6 in 30 the engine cylinder. The trip lever 13 is adapted to engage a cam face on the arm 8 in the usual manner for separating the electrodes. One of the terminals of the magneto generator is connected to a rod 22 which 35 is mounted in a sleeve of insulating material 23 and said sleeve is mounted in a boss 24 formed in the bracket 10 carrying the magneto. The outer end of said rod 22 terminates in a recess 25. The rod 22 has an extending rod 26 which is adapted to engage 40 the walls of said recess and thus form an electrical connection with the rod 22.

Mounted on the spark plug or supporting member 6 is a pin 27 which is adapted to 45 engage a recess 28 formed in a lug 29 carried by the bracket 10. This pin is set eccentric to the center of the opening 16, and, therefore, serves to hold the member 6 from any rotative movement relative to the bracket 10.

55 From the above, it will be apparent that I have provided a magneto generator wherein in the support for the fixed and movable electrodes is a self-contained unit adapted to be independently placed on the engine cylinder and said supporting member is held in place by the bracket.

It will also be noted that the fixed electrode has a sliding electrical contact with one terminal of the magneto generator, and, 60 therefore, the entire bracket may be readily 65

removed without disturbing any of the parts and the spark plug for the movable and fixed electrodes may be quickly replaced by a new part.

It is obvious that minor changes in the 70 details of construction and arrangement of parts may be made without departing from the spirit of the invention as set forth in the appended claims.

Having thus described my invention, what 75 I claim as new and desire to secure by Letters Patent, is:

1. In an ignition device, a fixed and a 80 movable electrode, a support therefor projecting beyond the face of the engine cylinder, a magneto generator, a bracket for supporting said generator, said bracket having an opening formed therein surrounding the projecting support for the electrodes, and means for holding the support for the 85 electrodes and the bracket in a predetermined relation to each other, and means for securing the bracket to the engine cylinder.

2. In an ignition device, a fixed and a 90 movable electrode, a support therefor projecting beyond the face of the engine cylinder, a magneto generator, a bracket for supporting said generator, said bracket having an opening formed therein surrounding the 95 projecting support for the electrodes, and means for securing the bracket to the engine cylinder, said support for the electrodes having a pin adapted to engage a recess in the bracket for holding the support from rotating movement in the bracket.

100 3. In an ignition device, a fixed and a movable electrode, a support for said electrodes, a magneto generator, a bracket for said magneto generator, means for securing the bracket to the engine cylinder, a terminal rod carried by the bracket for the magneto generator, and means whereby said fixed electrode has a sliding engagement with said terminal.

105 4. In an ignition device, a fixed and a movable electrode, a supporting member for said electrodes, a spring for holding said electrodes normally closed, a bracket independent of the support for the electrodes, a magneto generator carried by the bracket, means for securing the bracket to the engine cylinder, said bracket having means for surrounding the support for the electrodes and for holding the support on the engine cylinder.

110 5. In an ignition device, a fixed and a movable electrode, a supporting member for said electrodes, a spring for holding said electrodes normally closed, a bracket independent of the support for the electrodes, a magneto generator carried by the bracket, means for securing the bracket to the engine cylinder, said bracket having means for surrounding the support for the electrodes and for holding the support on the engine cylinder.

der, a rod terminal having a cup shaped recessed end carried by the bracket for the magneto generator, said fixed electrode having an extension adapted to make sliding engagement with the cup-shaped recess in the end of the terminal.

6. In an ignition device, electrodes, a support for said electrodes, a magneto generator, a bracket carrying said magneto generator and having an opening in which said support for the electrodes projects, said support having a shoulder adapted to be engaged by the bracket, whereby the support is held on the engine cylinder and additional means for holding said support for the electrode and the brackets in a predetermined position relative to each other.

7. In an ignition device, electrodes, a support for said electrodes, a magneto generator, a bracket carrying said magneto generator and having an opening in which said support for the electrodes projects, said support having a shoulder adapted to be engaged by the bracket, whereby the support is

held on the engine cylinder, a terminal rod 25 carried by the bracket for the magneto generator, one of said electrodes having an extension making sliding contact with a cup-shaped recess in the terminal rod.

8. In an ignition device, electrodes, a cylindrical support for said electrodes, a bracket, a magneto generator mounted on the bracket, said bracket having openings adapted to receive and fit an extension on said support, said bracket and support having interfitting means for holding the support from rotating in the bracket.

9. In an ignition device, electrodes, a cylindrical support for said electrodes, a bracket, a magneto generator mounted on 40 the bracket, said bracket having openings adapted to receive and fit an extension on said support, and a pin carried by the support, said bracket having a recess adapted to receive said pin.

In testimony whereof, I affix my signature.

ALBERT ERICKSON.
